CLAIM

We claim the ornamental design for syringe adapter and needle holder for medication, as shown and described.

DESCRIPTION

FIG. 1 is a perspective view of a syringe adapter and a needle holder, showing our new design (as connected), where the syringe adapter has a cylindrical element and the needle holder includes a hexagonal element and a cylindrical element;

FIG. 2 is a front view thereof, the back view being identical thereto;

FIG. 3 is a top view thereof, the bottom view being identical thereto;

FIG. 4 is a left-side view thereof;

FIG. 5 is a right-side view thereof;

FIG. 6 is a cross-sectional view thereof, along 6-6 in FIG. 3; FIG. 7 is a perspective view of the embodiment of FIG. 1, where the two pieces are shown as separated from each other for ease of illustration;

FIG. 8 is a perspective view of the syringe adapter of FIG. 1;

FIG. 9 is a front view thereof, the back view, the top view, and the bottom view being identical thereto;

FIG. 10 is a left-side view thereof;

FIG. 11 is a right-side view thereof;

FIG. 12 is a perspective view of the needle holder of FIG. 1, shown separately for ease of illustration;

FIG. 13 is a front view thereof, the back view being identical thereto;

FIG. 14 is a top view thereof, the bottom view being identical thereto;

FIG. 15 is a left-side view thereof; and,

FIG. 16 is a right-side view thereof.
